UNITED STATES PATENT OFFICE.

JOHN D. BURGESS, OF TUCSON, ARIZONA TERRITORY, ASSIGNOR OF TWO-THIRDS TO AUGUSTUS TAYLOR AND WILLIAM H. TAYLOR, JR., OF SAN FRANCISCO, CALIFORNIA.

BESSEMERIZING OR CONVERSION OF COPPER MATTES INTO BLISTER COPPER.

No. 877,292.

Specification of Letters Patent.

Patented Jan. 21, 1908.

Application filed April 26, 1906. Serial No. 313,581.

To all whom it may concern:

Be it known that JOHN D. BURGESS, citizen of the United States, residing at Tucson, in the county of Pima and Territory of Arizona, has invented certain new and useful Improvements in Bessemerizing or Conversion of Copper Mattes into Blister Copper, of which the following is a specification.

The invention relates to apparatus adapted for the purpose, taking the mattes in molten condition, direct from the matting or other furnace, continuously, or intermittently, as same is discharged from the matting furnace.

My invention has for its object, the substitution of peculiar apparatus for the ponderous converters now employed in the well known bessemerizing conversion of metals, and consists of novel apparatus and process, which will hereinafter be fully described.

In the following description reference is had to the accompanying drawings, forming a part of this specification.

In the drawings Figure 1 is a side elevation, in illustration of my invention. Fig. 2, is a top plan view of apparatus illustrated in Fig. 1. Fig. 3 is a transverse sectional view taken on line 3—3 of Fig. 1. Fig. 4 is a transverse sectional view taken substantially on line 4—4 of Fig. 1. Fig. 5 is a horizontal sectional view, taken on line 5—5 of Fig. 4, and Figs. 6 and 7 are respectively side and top plan views of detached castings forming a part of the apparatus constructed according to my invention. Fig. 8 is an enlarged detail view of one of the peep holes.

My general idea comprehends taking the mattes in molten condition direct from the matting or other furnace, and through the first stage of the operation, flowing same by gravity, the flow being accelerated by novel admission of blasts.

The generic idea comprehends flowing the molten mattes continuously, through a series of communicating passageways or boxes and with the flow accelerated by a series of similar admissions of blast.

In the conversion operation, I feed comminuted silica into the flowing molten mattes at one stage of the operation, and at another stage of the operation, I feed into the molten mattes, comminuted lime stone mixed with coke-dust, or other carbonaceous matter.

Apparatus deemed best adapted for use in the practice of my invention, may be stated as employing in the first stage of operation, a sheet steel box fifteen feet in length, two feet square on the outside, the box being securely anchored to an approved base by anchor bolts, or otherwise.

The box above described, is lined with some refractory material, or fire brick, leaving an inner circular, or oval opening extending from end to end of the box. It is contemplated fashioning the opening of sufficient size or capacity, to entertain any amount of matte discharged from any size or capacity of furnace to which the apparatus may be attached.

Air under pressure is admitted into the lined opening through the box, the same being fed from supply pipes upon opposite sides of the box. The air is fed into the lined opening through novel form of twyers, having suitable peep-holes at their outer ends, the peep-holes being arranged in line with the passage-way through the twyers.

The twyers are arranged providing passage-way from the air supply pipes, and made extending into the lined opening through the box, to a point suitably near its bottom. The twyers are disposed at an angle pointing downwardly and toward the discharge end of the lined box employed in the first stage of operation.

The flow of liquid matte is not only accelerated through operation of the blasts of air as introduced by me into the lined opening through the box, but the oxygen thus introduced under pressure, causes the chemical reaction, expressed by the following equation, thus : $2\text{FeS} + 3\text{O}_2 = 2\text{FeO} + 2\text{SO}_2$, quickly and continuously.

The desulfurized mattes is discharged from the first box, into the end of a second box, supported, anchored and lined, substantially as the box hereinbefore described.

The passage-way through the two boxes is connected by means of an interposed heavy cast iron spout, bolted to the ends of both boxes, and arranged therebetween, providing slightly greater fall than the endwise disposition of the two boxes.

It is designed to form the spout substantially U-shaped, leaving its upper side open, adapted for the introduction therethrough of finely comminuted silica, automatically fed.

from a hopper provided with a spout, and suitable cut-off to regulate the flow of silica in proper and needed proportion.

The second stage or box is provided with 5 twyers, substantially as employed with the first stage or box, and the same arranged extending from air supply pipes upon opposite sides of box. Now through introduction of silica, and admission of compressed air into 10 the flowing molten matte, the second reaction may be expressed thus:—

as being quickly and continuously accomplished.

15 The third stage or box is connected the same as the first and second stages, *i. e.* by a heavy cast iron spout, open on top and bolted to the ends of each box. This the third stage or box is provided with twyers the same substantially as similar twyers hereinbefore described, leading from air supply pipes upon both sides of the box and disposed, extending into the opening therethrough.

At the connection between the second and 25 third stages, or boxes, finely comminuted lime-stone, mixed with coke-dust, or other carbonaceous material is automatically fed into the open spout, under regulated control and from a stored supply thereof, in a hopper 30 substantially as employed for delivery of material between the first and second stages, or boxes. The added limestone gives greater fluidity to the siliceous-iron slag separated from the pure copper during the second stage 35 of this operation, and the coke-dust develops and restores heat lost during operation of the second stage.

It is designed, at the end of the third stage, or box, to flow the blister copper by gravity, 40 into some receptacle, carrying the remaining slag as float, adapted to be skimmed off leaving the blister copper to be ladled or tapped into desired molds.

Having thus outlined the general features 45 of novelty residing in my invention, I will now proceed to describe in detail the preferred form of apparatus employed by me, though obviously I do not confine myself to the precise form of means utilized nor is successful operation of the apparatus limited to 50 any particular size or dimension of parts.

Referring now to the several figures of drawing, A denotes suitable lining arranged in the boxes B, forming a part of the first, 55 second and third stage, and in the makeup of the apparatus.

The lining may be formed of fire brick, constructed and adapted, when arranged in place for leaving broken joints C therebetween.

60 The several boxes indicated, B, B', B'', are constructed with sides D having laterally disposed longitudinal edge flanges E.

The top and bottom of the several boxes

B, B', B'', consists of suitable plates F, adapted to overlie the flanges E of the side plates D. 65

G denotes anchor bolts extending down through the flanges E and the top and bottom plates F, as shown by Fig. 4, and leading down suitably into the apparatus supporting base H, the lower ends of the anchor bolts 70 being provided with any suitable shoe I, understood upon reference to Fig. 4.

It will be noticed upon reference to Fig. 1, that the top of the supporting base is disposed inclining downwardly from position of 75 receiving end of the apparatus. In the sides D of the several boxes B, B', B'', and through the box lining A, I provide openings J for introduction of peculiar twyers K, the latter providing passage-way from air supply pipes 80 L, extending along opposite sides of the boxes B, B', B''.

The twyers K are constructed of T joints M fashioned with angular passage-ways, substantially as indicated in Fig. 5, and a nozzle 85 N constructed to extend into the opening leading through the boxes, see Figs. 4 and 5, and with the nozzles N pointing downward and toward the discharge end of the several boxes B, B', B''. 90

A suitable peep hole is provided at O, in the T-joint M, the same being arranged in line with the air passage-way through the nozzles N, adapted for seeing "noses" when formed. The peep holes are closed with 95 clear mica retained in place adapted to be removed for the introduction of a metal bar through the nozzles to break-up any "noses" or "coolings" formed.

It is designed to arrange the inner end of 100 the nozzles of the first stage, or box, at the bottom of the opening therethrough, the inner ends of the nozzles of the second box, about two inches higher, and the same end of the nozzles, employed with the third box, two 105 inches higher than those in the second box.

P denotes the hoppers employed the same being designed for holding and feeding through means of suitable spouts Q, having cut-off valves, fluxes such as silica, limestone 110 and coke, or other carbonaceous dust, into the boxes, or stages of operation.

In the preferred form of apparatus the several stages, or boxes B, B', B'', are separated by a heavy casting S, formed with its top 115 side open, see Figs. 6 and 7.

The castings S have flanges T adapting them to be securely bolted to the respective box-ends, see Figs. 1 and 2.

The hoppers P are arranged to deliver the 120 fluxes into the molten material, through the open top spouts Q, see Fig. 1, and suitably arranged over the open spouts P, hoods U, are provided for carrying away the gases formed during the conversion operation. 125

V denotes any form of furnace to which my invention is adapted, at the discharge

end of last stage, or box, and a suitable tank W is provided for reception of the flowing blister copper, and remaining slag.

What I claim is

5. 1. The combination with an apparatus for bessemerizing or conversion of copper mattes comprising a suitably constructed box, of fire-brick lining in the box, the fire-brick lining being arranged so as to leave a longitudinal opening through the box, and the bricks being laid in broken joint arrangement, and means for feeding compressed air into the box, said means pointing downward and towards the discharge end of the box, substantially as described.

10. 2. In an apparatus for bessemerizing or conversion of copper mattes, comprising a box having receiving and discharge ends, twyers adapted for the admission of air therethrough, the twyers projecting downwardly into the box and at an angle toward the discharge end of the box.

15. 3. In an apparatus for bessemerizing or conversion of copper mattes, a series of communicating boxes, arranged end to end providing a continuous passage way through the series of boxes, hollow castings arranged between the adjacent ends of the several boxes in the series thereof, means adapting the

boxes and castings to be secured together, and means adapted for feeding finely comminuted silica and lime stone into the hollow castings, whereby to readily and quickly compel and assist the chemical changes desired.

35

4. In an apparatus for bessemerizing or conversion of copper mattes, comprising a box having receive and discharging ends, inclined twyers adapted for the admission of air into the box, the twyers being arranged to direct streams toward the discharge end of the box thereby assisting flowing action of material through the box.

5. In an apparatus for bessemerizing or conversion of copper mattes, having open end boxes arranged end to end in alinement, and provided with suitable openings, an incline base providing support for the said boxes, anchoring means, means for the admission of air into the boxes under pressure, and means adapted for the supply of fluxes into the boxes, substantially as described.

In testimony whereof I hereby affix my signature in presence of two witnesses.

JOHN D. BURGESS.
